United States Patent Office.

PETER CAMPBELL, OF CARROLLTOWN, PENNSYLVANIA.

Letters Patent No. 97,760, dated December 14, 1869.

IMPROVED RAILWAY-GATE.

The Schedule referred to in these Letters Patent and making part of the same.

To all whom it may concern:

Be it known that I, PETER CAMPBELL, of Carrollton, in the county of Cambria, and State of Pennsylvania, have invented a new and useful Improvement in Railroad-Gates; and I do hereby declare the following to be a full, clear, and exact description thereof, sufficient to enable others skilled in the art to which my invention appertains, to make and use the same, reference being had to the accompanying drawing, forming part of this invention, and in which—

Figure 1 is a top view;

Figure 2, a partial front view; and

Figure 3, an end view, from the line *y y*, fig. 1.

The gate which forms the subject of this invention, is held in position across the track by means of lever-catches, pivoted to the rails in such a manner that the weight of an approaching car or train depresses the rails and releases the catches, allowing the gate to be thrown back against its post when struck by the car or engine, and there held by a spring until the train has entirely passed, when the rails resume their former position, thereby releasing the spring which holds the gate open, and permitting it to swing across the track, where it is held as before.

The invention consists in the construction and arrangement of parts as hereinafter set forth.

I will now proceed to describe my invention in detail, referring to the drawings, in the several figures of which similar letters indicate like parts.

The gate proper is constructed in any suitable manner which will insure strength, and is hung to a post, *A*, by hinges, so constructed or arranged as to cause the gate to close by gravity.

B B' may represent the rails of the track.

The inner rail, *B*, is rigidly secured to the sleepers *C C' C'' C'''*, but the outer one, *B'*, is fastened only at *C* and *C''*, the other sleepers being cut away to allow of the depression of the rail.

D is a sort of platform at the side of the track, on which are pivoted bars *E E'*, having bevelled ends, and with shoulders *a a'*, between which the gate is held in position across the track.

F F' are levers, each of which is pivoted at one end to the rail *B'*, and at the other to one of the bars *E E'*.

These levers each have a fulcrum, *b*.

G G' are rods, with bent portions *c c'*, which have more or less elasticity.

These rods are pivoted at *d d'*, and are connected with the outer rail *B'*. Their office is to hold the gate open, as will be hereinafter described.

H H' are posts, against which the gate is thrown when struck by the car or engine.

They are each provided with a spring, *e*, with which the gate comes in contact, thereby preventing the post from being loosened or injured.

I I represent springs, applied to the gate for receiving and neutralizing the shock when the gate is opened by the car or engine.

The gate opens in either direction.

The operation is as follows:

Suppose a train to be approaching in the direction of the arrow, figs. 1 and 2. As soon as the engine reaches the section of track shown in the drawing, the rail *B'* will be depressed, at the same time depressing the bar *E*, through the medium of lever *F*. The engine then strikes the gate, or rather the springs attached to it, and throws it back against the post *H'*, where it is held by the bent portion of rod *G* springing up and preventing its return. As soon as the train has passed, the rail *B'*, being relieved of pressure, springs up, depressing the holder *G'*, which releases the gate, and elevating the catch *E*. The gate now swings by gravity to the position in which it is shown, where it is held between the shoulders *a a'* of the bars *E E'*.

The advantages of this gate are, that it is very simple and inexpensive, and is at the same time automatic and certain in its operation.

Having thus described my invention,

What I claim as new, and desire to secure by Letters Patent, is—

1. The self-closing gate, provided with springs *I*, as and for the purpose set forth.

2. The pivoted spring-holders *G G'*, when connected with the rail *B'*, for the purpose and substantially as described.

3. The catch-bars *E E'* and levers *F F'*, in combination with the spring-rail *B'*, when constructed and arranged to operate substantially as described.

4. The combination of the self-closing gate, the spring-rail *B'*, posts *H H'*, holders *G G'*, and catch-bars *E E'*, and levers *F F'*, all constructed and arranged to operate substantially as described.

To the above specification of my invention, I have signed my name, this 15th day of September, 1869, in the presence of two subscribing witnesses.

PETER CAMPBELL.
